(57) **CLAIM**

The ornamental design for a foldable packaging with printed surface ornamentation, as shown and described.

DESCRIPTION

The file of this patent contains at least one drawing/photograph executed in color. Copies of this patent with color drawing(s)/photograph(s) will be provided to the Office upon request and payment of the necessary fee.

FIG. 1 is an elevational view of an external side of the foldable packaging with printed surface ornamentation in a flat configuration and prior to folding; and, FIG. 2 is an elevational view of an opposite, internal side thereof.

The peripheral dashed broken lines represent boundaries of the claimed design; the peripheral dashed broken lines form no part of the claimed design.

“RDB Bioinformatics” and “Pathtrac” are registered trademarks, are owned by RDB Bioinformatics, LLC, are represented with dashed broken lines, and thereby form no part of the claimed design.

The dash-dot-dash lines depict fold lines and form no part of the claimed design.

The thickness of the foldable packaging with printed surface ornamentation forms no part of the claimed design.

Depth forms no part of the claimed design.
